UNITED STATES PATENT OFFICE.

WILLIAM H. MULLINS, OF SALEM, OHIO.

DESIGN FOR A BAKING-PAN.

SPECIFICATION forming part of Design No. 26,935, dated April 20, 1897.

Application filed March 3, 1897. Serial No. 625,903. Term of patent 14 years.

To all whom it may concern:

Be it known that I, WILLIAM H. MULLINS, a citizen of the United States, residing at Salem, in the county of Columbiana and State of Ohio, have invented and produced a new and original Design for Baking-Pans and Similar Culinary Utensils, of which the following is a description, due reference being had to the accompanying drawing, forming part of this specification, which illustrates in perspective a baking-pan configured by the characteristic features of my design.

Reference being had to the drawing and the letters thereon, it will be observed that in design my novel form of baking-pan consists of two semicylindrical sections distinguished by a median line of demarcation and collectively forming a cylindrical figure with closed ends, as shown.

The ends A B of such figure are slightly convex, while as a leading feature of this invention is employed a series of corrugations or projections C, which are independent of and parallel with each other, being individually designed and arranged to encircle the cylindrical body of the pan and to extend collectively from end to end thereof.

D indicates a surrounding flange which bisects corrugations C and constitutes a median line of demarcation between the pan-sections. 30

As illustrated, it will be observed that corrugations C are of comparatively narrow but uniform width and are arranged in close proximity one to the other, also that the ends A B are unornamented; but it will be noted that the spirit of the design resides in the transverse corrugations aforesaid, which may be varied somewhat in size without detracting from their general effect, and likewise the ends A B may be plain surfaces, ornamented 40 or unornamented, as desired.

Having thus described my invention, what I claim, and desire to secure by Letters Patent, is—

The design for a baking-pan, as herein 45 shown and described.

In testimony whereof I subscribe my signature in the presence of two witnesses.

WILLIAM H. MULLINS.
